US0D1069578S

(12) **United States Design Patent** (10) Patent No.: **US D1,069,578 S**
(45) Date of Patent: ** Apr. 8, 2025

(54) **LID FOR CONTAINERS**

(71) Applicant: **TETRA LAVAL HOLDINGS & FINANCE S.A.**, Pully (CH)

(72) Inventors: **Giulio Bertani**, Modena (IT); **Pietro Martini**, Modena (IT); **Daniele Golfieri**, Modena (IT); **Erica Lundström**, Lund (SE); **Kristian Jacobsson**, Lund (SE); **Francesca Tavoni**, Modena (IT); **Linda Luik**, Lund (SE); **Maurizio Filippini**, Modena (IT)

(73) Assignee: **TETRA LAVAL HOLDINGS & FINANCE S.A.**, Pully (CH)

(**) Term: **15 Years**

(21) Appl. No.: **35/519,974**

(22) Filed: **Feb. 7, 2023**

(80) **Hague Agreement Data**

Int. Filing Date: **Feb. 7, 2023**

Int. Reg. No.: **DM/227265**

Int. Reg. Date: **Feb. 7, 2023**

Int. Reg. Pub. Date: **Feb. 9, 2024**

CLAIM

The ornamental design for a lid for containers as shown and described.

DESCRIPTION

2. Lid for containers

4. Lid for containers

2.1 : Perspective

2.2 : Right side view

2.3 : Left side view

2.4: Front

2.5: Back

2.6: Top

2.7: Bottom

4.1 : Perspective

4.2 : Right side view

4.3 : Left side view

4.4: Front

4.5: Back

4.6: Top

4.7: Bottom

In the drawings, the broken lines depict portions of a lid for containers that form no part of the claimed design.
